UNITED STATES PATENT OFFICE.

WALTER W. WINSLOW, OF LAREDO, TEXAS, ASSIGNOR OF ONE-HALF TO ANDREW WINSLOW,
OF LAREDO, TEXAS.

LOCK.

No. 885,557.

Specification of Letters Patent. Patented April 21, 1908.

Application filed April 22, 1907. Serial No. 369,644.

To all whom it may concern:

Be it known that I, WALTER W. WINSLOW, a citizen of the United States, residing at Laredo, in the county of Webb and State of Texas, have invented a new and useful Lock, of which the following is a specification.

This invention has reference to improvements in locks, and its object is to provide a lock which, when one knob is turned, will 10 give an alarm and which may be so arranged that the door may or may not be opened by the turning of said knob but which door may be always opened by the turning of the other knob.

15 The invention consists essentially in a door lock having but one lock bolt which, when the door is opened, is automatically locked in the inactive position but which when the door is closed automatically locks the door 20 against unlocking from the side of the door remote from that carrying the lock except by a person possessed of a suitable key, although provision is made for so connecting that knob which, for convenience, may be called the 25 outside knob, to the bolt-operating mechanism that the latter may be operated by the outside knob when so desired. An alarm mechanism is arranged in constant communication with the outside knob so that the latter 30 cannot be turned without sounding an alarm, and this whether the outside knob be connected or disconnected from the bolt-operating mechanism.

The invention will be fully understood 35 from the following detailed description, taken in connection with the accompanying drawings forming part of this specification, in which,—

Figure 1 is a face view of a lock constructed 40 in accordance with my invention; Fig. 2 is a face view, with parts in section, showing the lock with the face plate removed; Fig. 3 is a cross section through the lock and door to which it is applied, parts being shown in elevation; Fig. 4 is a detail view showing the 45 manner of connecting the outer knob to the ringing mechanism; Fig. 5 is a detail view of the roll-back; and Fig. 6 is a detail view of the connecting device for coupling the out- 50 side knob to the lock-bolt-operating mechanism.

Referring to the drawings, there is shown a casing 1 which may be of the ordinary rectangular shape with side walls of sufficient

depth to form a chamber for certain parts of 55 the working mechanism of the lock, which chamber is inclosed by a cover 2 similar to that of an ordinary lock. The front wall of the casing is provided with a slot 3 for the passage of the locking head 4 of the sliding 60 lock-bolt 5. This lock-bolt 5 may be of the usual type with a recess 6 for the reception of the bit of a key introduced into the inside of the casing through a keyhole 7.

The shank of the lock-bolt 5 may pass be- 65 tween fixed studs 8, and at its rear end it is pivotally connected to one end of a link 9, the other end of which is pivoted, as indicated at 10, to the casing. This link 9 is under the control of a flat spring 11 held by lugs 70 12 cast on the casing, and the tendency of the spring 11 is to project the head 4 of the lock-bolt 5 through the slot 3 to the extreme point of its travel.

The link 9 is provided with a curved recess 75 13 to receive the cylindrical portion of a roll-back 14 provided with radial lugs 15 and seated in the casing 1 in the usual manner so that when moved by a knob in the manner to be hereinafter described the link 9 will be 80 moved about its pivot 10 and against the action of the spring 11 so as to cause the head 4 of the lock-bolt to be moved into the casing. This roll-back is provided with a bore 16 which receives the reduced portion 85 17 of the shank 18 of a knob 19, the said shank 18 being provided with an axial, longitudinal, cylindrical bore 20. Seated in the portion 20 of the knob shank 18 is the cylindrical portion 21 of a knob spindle 22, which latter extends through the casing 1 and is of sufficient length to pass through a door 23 and receive a knob 24 on the opposite side of said door from that occupied by the lock casing 1. The door is provided with a suit- 95 able perforation 25 for the passage of the spindle 22, and this perforation has near the side occupied by the lock casing 1 a countersunk portion 26 of sufficient size to receive a collar 27 made fast on the knob spindle 22 by 100 a screw 28 or otherwise.

It will be seen that when the shank 29 of the knob 24 is in contact with the usual wearing plate 30 on the outside of the door and the sleeve 27 is suitably fastened to the 105 knob spindle 22, the latter is prevented from longitudinal movement with reference to the door but may be freely rotated therein. The

- end 21 of the knob spindle 22 enters the knob shank 18 and is there provided with a through slot 31 of considerable length for longitudinal adjustment of the spindle 22. 5 This slot is engaged by a pin 32 passing through to a radial perforation in the knob shank 18 and the pin is provided at its outer end with a manipulating head 33. This pin 32 is carried by a spring 34 so shaped as to 10 partially encircle and grasp the shank 18 of the knob 19 and hold the pin 32 so that its inner end enters the slot 31 in the spindle end 21, but this spring has sufficient elasticity to permit the withdrawal of the pin 32 15 from the slot 31 so that the pin may be moved out of coincidence with the radial passage through the shank 18 so that the knob spindle 22 will be disengaged from the knob 19.
- 20 The roll-back 14 may be fixed to the reduced portion 17 of the shank 18 by means of a set-screw 35 whether the reduced portion 17 on the bore of the roll-back is cylindrical or otherwise shaped since the set-screw 35 25 serves to secure the knob 19 to the lock. The knob 19 will constitute the inner knob of the door, by which is meant that knob which may be always manipulated to turn the lock without the necessity for a key or 30 other means for throwing the bolt, and since the knob 19 is in constant operative connection with the roll-back 13 the simple turning of the knob 19 in either direction will retract the head 4 of the lock-bolt. 35 When the pin 32 is so set as to engage in the slot 31 the two knobs 19 and 24 are connected together and the roll-back and lock-bolt may be operated by either knob, but when the pin 32 is withdrawn from the slot 31 the 40 knob 24 will not operate the lock-bolt, and, consequently, the only manner in which the lock bolt may be turned from what may be termed the outside of the door is by means of a key introduced through the keyhole 7.
- 45 Now, in order that the knob 24 may not be manipulated for any purpose without giving notice to a person located on the other or inner side of the door, there is secured on the spindle 22 a gear wheel 36 seated in a suitable 50 recess 36' formed on the inner face of the door and this gear wheel is in mesh with a gear pinion 37 mounted on the end of a shaft 38 extending through the lock casing 1 and its cover 2 and there engaging the ringing 55 mechanism of a suitable bell 39 mounted on the cover 2 of the lock. This bell may be of any suitable or well-known form which will give audible indication when its interior mechanism is moved by the gear wheel 36 60 and pinion 37 through the shaft 38. The mechanism of this bell, which in itself forms no part of the present invention, is not shown in the drawings.

It will be seen that the alarm bell will give 65 an audible signal whenever the outer knob 24

is turned so that the turning of this knob will indicate to a person on the inner side of the door that the outer knob has been turned. This bell, therefore, operates as an ordinary door bell with the additional function of giving notice of a surreptitious attempt to gain access through the door, should such an attempt be made. 70

Fast to the front or face plate of the lock there is a spring 40 extending across said face plate and beyond the same adjacent to the head 4 of the lock-bolt. The free end of this spring carries a block 41 which, when the head 4 is withdrawn in the lock casing is impelled by the spring 40 into the path of said lock-bolt and therefore holds the same from being again projected by the spring 11 when the knob 19 or 24 is released. Now, when the door is closed, this block 41 will be engaged by the usual keeper 42 on the door 85 casing before the door has quite reached the closed position, and this block 41 will be held stationary as the door continues toward the completely closed position. The result is that the block 41 is moved out of the path of 90 the head 4 and when the casing 1 is coincident with the keeper 42 the head 4 is entirely free and is impelled into engagement with the keeper 42 by the spring 11. 95

When the latch-bolt 5 is operated by either one of the knobs so that its head 4 is withdrawn from the keeper 42 the resiliency of the spring 40 will cause the door to be thrown open, this spring being made strong enough for the purpose, and when the door is closed 100 the spring 40 will retard its movement after the block 41 engages the keeper 42 and will therefore act to an extent as a spring check for the door. 105

Claims.

1. A lock provided with a lock-bolt, a knob in constant operative relation thereto, another knob, connections between the last-named knob and the first knob, and means for coupling the second knob to the first 110 knob comprising a pin movable radially through the shank of one knob into engagement with the connections from the other knob and having one end formed into a handle, and a spring embracing said shank and 115 carrying said pin.

2. A door lock having a spring-actuated lock-bolt, knobs in operative relation thereto, and a spring-actuated locking member for the lock-bolt exterior to the lock casing and 120 movable across the end of the casing and beyond the latter into the path of the corresponding end of the lock-bolt in position to be engaged by that portion of the keeper which houses the lock-bolt. 125

3. A lock comprising a lock-bolt, a roll-back for operating the same, a knob having a hollow shank carrying said roll-back, another knob, a spindle fixed thereto and entering the hollow shank of the first-named 130

knob, means for coupling the shank of the first-named knob and the spindle together, and a collar adjustably mounted on the spindle for fixing the relation of the second-named knob to the lock irrespective of its connection to the first-named knob.

In testimony that I claim the foregoing as

my own, I have hereto affixed my signature in the presence of two witnesses.
